(57) **CLAIM**

The ornamental design for a showerhead, as shown and described.

DESCRIPTION

FIG. 1 is a front perspective view of a showerhead, showing my new design with a hand sprayer attached to a main showerhead;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top plan view of FIG. 1;

FIG. 7 is a bottom plan view of FIG. 1;

FIG. 8 is a rear perspective view of FIG. 1;

FIG. 9 is a front perspective view thereof, illustrated with the hand sprayer detached from the main showerhead;

FIG. 10 is a front elevational view of FIG. 9;

FIG. 11 is a rear elevational view of FIG. 9;

FIG. 12 is a left-side elevational view of FIG. 9;

FIG. 13 is a right-side elevational view of FIG. 9;

FIG. 14 is a top plan view of FIG. 9;

FIG. 15 is a bottom plan view of FIG. 9; and,

FIG. 16 is a rear perspective view of FIG. 9.

The broken lines in the figures depict flexible hose portions and nozzles of the showerhead that form no part of the claimed design. The remaining broken lines depicting a shower pipe show environmental matter, and form no part of the claimed design.

1 Claim, 15 Drawing Sheets
